UNITED STATES PATENT OFFICE.

WILLIAM E. WALSH, OF LOWELL, MASSACHUSETTS, ASSIGNOR TO DRAPER CORPORATION, OF HOPEDALE, MASSACHUSETTS, A CORPORATION OF MAINE.

BUILDER MECHANISM FOR SPINNING OR WINDING MACHINES.

1,299,639.

Specification of Letters Patent.

Patented Apr. 8, 1919.

Application filed June 21, 1918. Serial No. 241,250.

To all whom it may concern:

Be it known that I, WILLIAM E. WALSH, a citizen of the United States, residing at Lowell, in the county of Middlesex and State of Massachusetts, have invented an Improvement in Builder Mechanism for Spinning or Winding Machines, of which the following description, in connection with the accompanying drawings, is a specification, like characters on the drawings representing like parts.

This invention relates to improvements in spinning machines, and more particularly to the builder mechanism employed in such machines for winding yarn on receivers or bobbins to be subsequently used as filling or weft during the weaving of cloth.

In that general type of looms wherein the filling is replenished prior to complete exhaustion of that in the running shuttle, it is usual to provide a reserve supply of filling on the bobbins or other receivers, part, at least, of which will remain upon the bobbin or receivers after the working supply has been substantially exhausted and the "feeler" mechanism has called for replenishment. Many devices have been devised for placing this reserve supply of filling or "bunch", as it is sometimes called, on the bobbins or receivers during the spinning operation, and one of the objects of the present invention is to provide a mechanism for this purpose which shall be simple in construction and effective in operation.

Another important feature of the present invention consists in a builder mechanism which, by manual manipulation, may be set to start the winding of the bunch at any desired point along the length of the bobbins or receivers and upon starting the machine will automatically vary the traverse until the bunch is completed and then insure resumption of regular service traverse commencing at the base of the bobbin or receiver.

Another feature of importance is the facility with which the attendant may manually adjust the mechanism to place the bunch on any desired part of the bobbin or receivers without disassembling or changing the construction. Other features of the invention will best be made clear from the following description and accompanying

drawings which disclose one good practical form of the invention.

In the drawings:

Figure 1 is a view of a portion of a worsted spinning machine provided with the present invention;

Fig. 2 is a front view of the parts, certain portions being broken away for clearness of illustration;

Fig. 3 is a diagrammatic view of a bobbin having a bunch wound thereon, and showing the location of the bunch some distance above the base of the bobbin;

Fig. 4 is an enlarged plan view, showing more particularly the traverse slide and its associated parts;

Fig. 5 is a side view of the parts shown in Fig. 4;

Fig. 6 is a section on the line 6—6, Fig. 4;

Fig. 7 is a section on the line 7—7, Fig. 4.

The main supporting frame of the machine may be of any desired construction, and as shown in the present instance, the invention comprises the end frame, the members 1 connected by longitudinally-extending rails 2, 3, the latter of which constitutes a spindle-bearing rail. In the present instance of the invention, it is shown and will be described in connection with a well-known form of worsted spinning machine, but it is to be understood, of course, that it is not confined to such use, and may be advantageously employed in connection with other forms of spinning machines.

Mounted on the spindle rail 3 are the spindles 4 which, as usual in worsted spinning machines, extend upwardly through a way-plate or lifting rail 5. Each of the spindles 4 is adapted to support a yarn receiver or bobbin 6 which extends upwardly into the usual cap 7, Fig. 1, mounted upon the top portion of the respective spindles 4 or supported in any other desired or suitable manner. Rotary movement is imparted to the yarn receivers or bobbins by means of the driving bands or belts 8 in the usual manner. Mounted in suitable bearings on the machine frame is the cam shaft 9 having secured thereto for rotative movement therewith the builder cam 10. Pivotally mounted on the machine at 11 is the arm 12, the lower end portion of which is adapted to be oscil-

lated by the builder cam 10 as usual. In the present instance, the arm 12 has mounted thereon at 13, the roller 14 which bears upon the builder cam 10. Pivotaly mounted at 5 the lower portion of the machine frame is the swing arm 15 which may be of usual construction. Mounted for rising and falling movement on the swing arm 15 is the bracket 16 carrying a roller 17 adapted to bear upon 10 the arm 12, the construction being such that as the swing arm actuator 12 is operated by the builder cam, the swing arm 15 will be actuated and the amplitude of its movement will be controlled by the position of 15 the bracket 16 carrying the roller 17. The bracket 16 has connected thereto the rack 18 which engages a pinion 19 connected to the shaft 20, whereby the position of the bracket 16 may be adjusted during the building 20 operation, as usual in worsted spinning machines. Connected to the shaft 20 and also to the swing arm 15 is the traverse screw 21 which transmits traverse motion from the builder mechanism thus far described, to 25 cause relative traverse movement between the yarn receivers and yarn guides or caps.

Suitably supported for sliding movement on the machine frame is the traverse slide 22 to which is secured a chain 23 or other 30 flexible connection extending between the traverse slide and a block 24 on the lower end portions of the lifter rods 25 which at their upper ends are secured to the way-plate or lifter rail 5. The chain or flexible 35 connection 23 may be conveniently guided between the traverse rail 22 and the lifter rods 25 by the guide pulleys 26. The parts thus far described may be of any usual or suitable construction, as common in the 40 art,—or as pointed out by the patent to Leonard, No. 1,212,650, dated June 16, 1917.

Mounted for rotary movement on the traverse slide 22 is a cam shaft 27. The traverse slide 22 may have a bearing 28 of 45 sufficient extent to maintain the cam shaft properly alined in its bearing. Secured to the cam shaft 27 is a cam 29, Figs. 4, 5 and 7, which is adapted to bear against the end of a slide member 30 mounted for sliding 50 movement in a guide or bracket 31 secured to the traverse slide 22. In the present instance of the invention the guide 31 may have its lower portion formed integral with the traverse slide 22 and be provided with a 55 cap 32 secured to the guide 31 by suitable means such as the screws 33 for holding the sliding member 30 in guiding relation with its guide. For the purposes of identification the sliding member 30 may be hereinafter 60 designated a plunger, and as shown in the present instance of the invention, it is provided with an enlarged head portion 34 against which is seated the end of the traverse screw 21.

65 The plunger 30 is preferably provided

with a roller 35 at its end opposite the head 34 which is adapted to bear against the cam 29 carried by the cam shaft 27. From the construction thus far described it will be apparent that should the cam 29 be turned to 70 present different portions thereof to the plunger 30, the traverse rail 22 on which the cam is carried, will be correspondingly shifted or moved since the head 34 of the plunger rests against the end of the traverse 75 screw 21.

Secured to the cam shaft 27 is a ratchet wheel 36 having a series of teeth 37 and a blank space 38. Mounted for rocking movement on the cam shaft 27 is a hub 39 having 80 extending therefrom a pawl-carrying arm 40 to which is pivotally connected as at 41, a pawl 42 adapted to coact at times with the ratchet teeth 37 of the ratchet 36. Also extending from the hub 39 is an operating arm 85 43, to the lower end portion of which is pivotally mounted as at 44, a sleeve 45. Extending through the sleeve 45 is a rod 46 having connected thereto the stop collars or nuts 47. The rod 46 may be operated from 90 any convenient part of the machine to actuate the pawl, but in the present instance of the invention this rod is extended to and connected with an arm 48 rotating with the builder cam 10, as indicated in Figs. 1 and 2. 95

Secured to the longitudinal rail 2 of the machine is a supporting stand 49 having at its upper portion a guide for directing the movement of the traverse rail 22 and assist in supporting the weight of parts carried by the traverse slide. In the present instance of the invention, the stand 49 has a slotted guideway 50, Fig. 1, through which passes the cam shaft 27 which thereby serves also as a guiding and supporting means for the 100 105 traverse rail and the parts carried by it.

Connected to the cam shaft 27 is a hand lever 51 adapted at times to be operated by the attendant. In the present instance of the invention, the hand lever or crank 51 is 110 secured to the cam shaft 27 outside the guideway 50, thereby serving also as a steadyng means for the traverse rail 22 and the parts carried thereby.

Connected to the pawl-carrying arm 40 115 is a weight 52, Figs. 2 and 5, which normally holds the pawl-carrying arm and its connected parts with the arm 40 resting upon the stop 53 secured to the traverse slide 22 or a bracket connected therewith, 120 the construction being such that the pawl-carrying arm 40 will normally tend to rest against the stop 53 in the position indicated in Figs. 2 and 5. A finger 54 is extended over the pawl 42 to prevent the latter from 125 being thrown too violently away from the ratchet wheel 36 when the latter is turned.

A holding pawl 55 pivotally connected at 56 to the traverse slide 22 or to a bracket 57 mounted thereon, has a weighted end 58 130

which normally holds the end of the pawl in engagement with the ratchet teeth 37 and serves to prevent rotary movement of the ratchet wheel 36.

- 5 In placing the preliminary windings or a "bunch", so-called, upon the yarn receivers or bobbins, it is desirable to locate the primary windings or bunch at different distances from the head of the bobbin in order 10 that it may be properly disposed relative to the feeler mechanism. At the same time, the regular traverse windings placed upon the receivers or bobbins should start at the base of the bobbin or receivers in order to get the 15 proper amount of yarn thereon. This condition is true with respect to any yarn receivers or bobbins used in a feeler loom, and is particularly desirable where the bobbin is of the slotted type. In either event, however, the present invention provides means 20 whereby the attendant may turn the cam 29 into such position relative to the plunger 30 that the preliminary windings or bunch may start to be wound at any point in the longitudinal length of the yarn receiver or bobbin, and be located at any part thereof, and at the same time the service windings may be caused to commence at the lower or head end of the yarn receivers or bobbins.
- 25 In the present instance of the invention, the cam 29 is shown as of a character to provide a bunch or preliminary windings substantially like that shown at *a* on the yarn receiver or bobbin 6, Fig. 3. In forming such bunch, the attendant, before starting the machine, turns the cam shaft 27 by the hand lever or crank 51, to bring the desired low part of the cam 29 against the end of the plunger 30, thereby permitting the 30 traverse slide 22 to move to the left and force lower the way-plate or guide rail 5 and the bobbins or yarn receivers. The point to which the yarn receivers or bobbins will be lowered relative to the fixed caps will obviously depend upon the position of the cam 29; consequently, by properly manipulating the cam, the preliminary windings or bunch may be started at any point of the bobbin or yarn receiver. As hereinbefore pointed out, it is desirable that the 35 service windings shall commence at the base or head of the bobbins. To this end the cam 29 is so formed that when the high part thereof acts against the end of the plunger 40, the traverse slide 22 is moved to the right a sufficient distance to thereby lift the way-plate or guide rail 5 and raise the bobbins relative to the fixed caps to start the service winding at the base or head of the bobbins.
- 45 The attendant having set the cam to commence the preliminary or bunch windings at the desired part of the yarn receivers or bobbins, the machine is started and as the lifter cam rotates, the pawl 42 will be actuated to step the ratchet wheel 36 along and thereby rotate the cam 29 until the end of the pawl reaches the toothless portion 38 of the ratchet wheel 36, at which time the preliminary windings or bunch will have been completed and the cam 29 reached a position 70 to start the service windings at the base of the bobbins or yarn receivers. The preliminary or bunch windings, as will be observed from the above description, commences at the top of the primary or bunch windings 75 and proceeds downwardly, and as layer after layer of the primary or bunch windings is laid, there is an increase of gain downwardly due to the action of the cam 29; and when the preliminary or bunch windings have 80 been completed and the pawl has reached the toothless portion of the ratchet wheel 36, service traverse windings will be started from the base of the bobbin or yarn receivers 85 upwardly.
- What is claimed is:—
1. In a machine of the class described, the combination of a series of spindles for holding yarn receivers, yarn guiding means for directing yarn to the receivers, means for effecting relative service traverse between the yarn guiding means and receivers, means including a cam in the train of mechanism for effecting service winding and means for setting the cam to commence preliminary windings at any desired point longitudinally of the yarn receivers, and means acting automatically through the cam for modifying the traverse. 90
2. In a machine of the class described, the combination of a series of spindles for holding yarn receivers, yarn guiding means for directing yarn to the receivers, traversing mechanism for effecting relative service traverse between the yarn guiding means and receivers, a cam in the train of mechanism for effecting service traverse, means for setting the cam to commence the windings at any desired point on the receivers, and means for automatically operating the cam during 105 primary windings to modify the preliminary windings placed on the receivers. 110
3. A machine of the class described comprising a series of spindles for supporting yarn receivers, coöperating yarn guiding means, a cam and connections for causing relative movement between the yarn receivers and guiding means to lay the yarn by service windings on the receivers, said connections including a second cam, manual 115 means for setting the second cam to commence windings at any point on the receivers, and means for automatically actuating said second cam until the preliminary windings are completed and then permitting 120 the second cam to remain idle in the train of said connections during the service windings. 125
4. In a machine of the class described, the combination of a series of yarn receivers, co- 130

- operating yarn guides, a train of mechanism for producing relative traverse between the yarn receivers and yarn guides including two cams, means for continually actuating one of said cams during the winding of the yarn on the receivers, means for actuating the other of said cams for a predetermined number of windings for modifying the traverse imparted by the continually-actuating cam, and means for rendering said second cam idle after the preliminary windings have been completed.
5. A builder mechanism for spinning machines, comprising a series of spindles, yarn receivers supported thereby, a series of yarn guides for directing yarn to the receivers, a builder cam and connections for effecting relative traverse between the receivers and yarn guides, a second cam in the train of connections for modifying the action of the builder cam, manual means for setting the second cam, ratchet and pawl mechanism for automatically operating the second cam for a predetermined number of traverses and 25 then becoming ineffective to permit service traverse to be transmitted through the second cam.
6. A builder mechanism, comprising a builder cam, a swing arm actuated by the cam, a slide, a second cam mounted on the slide, connections between the swing arm and second cam for imparting movement to the slide, manual means for setting the second cam to locate the commencement of the windings, and means for automatically operating the second cam for a predetermined number of traverses to modify the traverse movement imparted to the slide by the builder cam.
- 40 7. A builder mechanism, comprising a builder cam, a traverse slide, means between the builder cam and traverse slide for moving the latter from the builder cam, including a cam on the slide, and means for manually operating the cam on the slide to vary the relation of the builder cam and slide.
8. A builder mechanism, comprising a builder cam, a traverse slide, connections between the builder cam and slide for operating the latter from the former, said connections including a cam on the slide, manual means for setting the cam to determine the point where the traverse is to commence, and automatic means for operating the cam 50 on the slide to modify the traverse imparted to the slide by the builder cam.
5. A builder motion comprising a builder cam, a swing arm actuated by the builder cam, a traverse bar, a cam and plunger on the traverse bar, means between the swing arm and plunger for imparting movement to the traverse bar, and means for operating the cam on the traverse bar to change the relation of the plunger and bar for modifying the traverse movement imparted to the bar by the swing arm acting through the plunger.
10. In a machine of the class described, the combination of a builder cam, a swinging arm operated by the builder cam, a series of bobbins and yarn guides, means operated from the swinging arm for relatively traversing the bobbins and guides, said means including a second cam, attendant-controlled means for setting the second cam in different positions to start windings from different points along the bobbins, and means for automatically operating the second cam to modify the action of the builder cam and commence service windings from the base or head of the bobbins when the preliminary windings are completed.
11. In a machine of the class described, the combination of a builder cam, a swinging arm operated by the builder cam, a series of bobbins and yarn guides, means operated from the swinging arm for relatively traversing the bobbins and guides, said means including a second cam, attendant-controlled means for setting the second cam in different positions to start windings from different points along the bobbins, and mechanism for automatically turning the second cam step-by-step to modify the traverse imparted by the builder cam.
12. In a machine of the class described, the combination of guides for directing yarn to yarn receivers, a builder cam, and connections between the builder cam and guides for relatively traversing the yarn receivers and guides, said connections including a manually adjustable cam for determining the point on the receivers at which the windings shall commence and means acting automatically upon the manually adjustable cam to commence service windings at the base of the receivers after a predetermined number of preliminary windings have been wound upon the receivers.

In testimony whereof, I have signed my name to this specification.

WILLIAM E. WALSH.
